(57) **CLAIM**

The ornamental design for a portable display as shown and described.

DESCRIPTION

FIG. 1 is a perspective view of a portable display showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the portable display where the portable display is in a folded state;

FIG. 10 is an enlarged view of portion 10 shown in FIG. 1; and,

FIG. 11 is an enlarged view of portion 11 shown in FIG. 8. The broken lines adjacent to the shaded areas depict boundaries of the portable display that form no part of the claimed design. The other broken lines in the drawings depict portions of the portable display that form no part of the claimed design. The areas adjacent to the broken lines and not shaded depict portions of the portable display that form no part of the claimed design. The dot-dash broken lines in FIGS. 1, 8, 10 and 11 represent boundaries of the enlarged portions and form no part of the claimed design.

1 Claim, 11 Drawing Sheets
